UNITED STATES PATENT OFFICE.

ALBERT ROTH, OF SAN FRANCISCO, CALIFORNIA, ASSIGNOR TO ROTH, WINTER & WALSH, A COPARTNERSHIP, OF SAN FRANCISCO, CALIFORNIA.

MEAT-LOAF FORMER.

Application filed March 15, 1926. Serial No. 94,709.

This invention relates to apparatus for forming meat loaves by pressure and cooking, especially ham loaves.

The objects of the invention are to provide apparatus which will more effectively perform the desired functions than the apparatus heretofore available and in a manner found best in long experience in this work by applicant.

10 Briefly described the apparatus comprises an elongated cooking receptacle into which the boned ham or other meat is forced by means of a telescopic pressure cover fitting within the receptacle, and it is to the specific construction of the apparatus that my invention relates.

In the drawings accompanying this application Figure 1 is an elevation of my improved device with portion broken away to 20 reveal the inner construction and Figure 2 is a plan view of the receptacle only with the telescopic cover omitted.

The receptacle 1 is preferably a solid aluminum or other metal casting of elongated form reduced and rounded at one end at 2 as best shown in Figure 2, to receive the neck of a ham, and at which reduced end it is provided with a series of perforations 3.

30 The receptacle may have a flat bottom but is here shown as with a rounded bottom so as to form by coaction of a similarly rounded pressure cover 4 a round ham loaf.

Underneath the rounded bottom are transverse ribs 5 connected by a central longitudinal rib 6 forming leveling legs to sustain the receptacle when applying the pressure, while at opposite ends of the receptacle project open yokes or lugs 7 adapted for locking the cover after applying pressure to the same.

40 The cover 4 is of rigid cast construction and telescopes freely into the receptacle and is inwardly rounded as indicated, while on top of the cover extend a pair of aligned yokes 8 preferably cast integral therewith.

Extending through these yokes is a pressure bar 9 provided at both ends with dependent pivoted levers 10 adapted to pass into the slots of lugs 7 and engage the same 50 by any of a series of pins 11 projecting from opposite sides of both levers.

At the central lower portion of bar 9 is another integral yoke 12 forming a guide and retainer for a series of arched spring blades 13 held in position by a pin 14.

The lower ends of this arched spring rest slidably upon flattened seats on the cover and are guided against lateral deflection by longitudinal ribs 15 formed at the sides of the flat seats.

Normally this spring forces the bar to the outward limits permitted by the yokes 8, and stop lugs 16 formed on the bar limit the forced movement of the bar in direction of the cover relative to the same, while lugs 17 are provided on the bar to position it longitudinally with respect to the cover.

In operation a boned ham is placed into the receptacle with neck of the ham arranged in the perforated end of the same 70 the cover is fitted and under pressure applied to the bar the springs are compressed until the lugs 16 meet the cover and the cover compresses the ham to the desired degree.

75 During application of the pressure the levers 10 are held out and when the cover has descended sufficiently the levers are brought together and the pins 11 engaged with the lugs 7 to lock the cover in place.

The pressure form is then placed into the cooking vat and as the meat cooks the shrinkage is taken up by expansion of the spring.

80 During the cooking process the perforated end of the receptacle insures the proper cooking of the tougher end of the ham to uniformity with the remaining portion, a result heretofore not obtained.

Upon removal from the vat and cooling, 85 the levers 10 projecting freely downward below the lugs 7 and being smooth along their inner walls permit easy releasing by simply pulling out with the hand, and it should also be noted that the pins 11 may be rested 90 on top of the lugs 7 at either or both ends in applying or removing the cover.

I claim:

1. A meat loaf former comprising an elongated receptacle with one end reduced in cross sectional area and provided with perforations at the reduced end only.

2. A meat loaf former comprising an elongated receptacle provided with a lid arranged for compressing the contents of the receptacle and a group of holes through the receptacle at one end only to provide for more intense boiling action at said end.

ALBERT ROTH.
